GEORGE H. REYNOLDS, OF MANSFIELD DEPOT, CONNECTICUT, ASSIGNOR TO THE REYNOLDS ICE MACHINE COMPANY, OF NEW YORK, N. Y., A CORPORATION OF NEW YORK.

VALVE MECHANISM FOR AIR-COMPRESSORS.

973,211.

Specification of Letters Patent. Patented Oct. 18, 1910.

Original application filed October 31, 1906. Serial No. 341,391. Divided and this application filed March 25, 1907. Serial No. 364,516.

To all whom it may concern:

Be it known that I, GEORGE H. REYNOLDS, a citizen of the United States, residing in Mansfield Depot, county of Tolland, and 5 State of Connecticut, have invented a new and useful Improvement in Valve Mechanism for Compressors, of which the following is a description.

This invention relates to valve mechanisms, and particularly to outlet valves, which may be used in any relation but which I have shown particularly adapted to the compression mechanism of a refrigerating apparatus, more particularly shown and described in my application, Serial Number 15 341,391, filed October 31st, 1906, of which this application is a division.

Among the objects of my invention may be noted the following: to provide an outlet 20 valve, the structure of which is adapted for practically any use, and which, wherever used, will be strong and durable, certain in action and effective for the purposes; to provide an outlet valve, the movements of 25 which are always under comparative control overcome only by the force of the compressed fluid during operation; and to provide an outlet valve mechanism which has its operative movements in right lines without possibility of variation therefrom.

With the above objects in view, and others which will be detailed during the course of this description, my invention consists in the parts, features and combinations of elements 35 hereinafter described and claimed.

In order that my invention may be understood, I have provided drawings in which the figure is an enlarged sectional detail of my outlet valve made according to my invention.

Generally speaking, in my refrigerating apparatus, made the subject of the application aforesaid, the air or gas which is employed as the circulating or refrigerating 45 medium, is pumped or forced into the receiving or return chamber or pipe of a compression mechanism by means of a primer pump located in the bottom of the compression tank. The frame has a hollow head at 50 opposite ends close to the ends of the piston cylinder, providing chambers within which the air or other gas enters, and in which the inlet and outlet valves operate.

The particular invention, of this applica-

tion, is the outlet valve mechanism which is 55 shown in all its details in the figure, and wherein the valve-head 26 is carried by the stem 27 journaled in sleeve 28, in turn journaled at its forward end in the spider 29, which latter is peripherally screw-threaded 60 to coöperate with the ring 30, which in turn is peripherally screw-threaded to coöperate with the wall 31 of the heads respectively containing the valve chambers 8 and 9. The ring 30, at its outer end, is provided with a beveled flange 32 providing a seat for the valve-head 26. The other end of the sleeve 28 is journaled in the cap 33, which is peripherally screw-threaded at its inner end to coöperate with the head 34 of 70 chamber 9, and is provided centrally with the bore 35, which latter is enlarged at its open end to provide the chamber 36.

The sleeve 28 slides freely in the bore 35 of the cap 33, and near its outer end is provided with the collar or flange 37 affording a bearing for the coiled-spring 39, which surrounds said sleeve, and the other end of which spring operates within the chamber 36, the spring thus exercising a normal 80 tendency to force the sleeve outwardly and the sleeve, in consequence, exercising a normal tendency to force the valve-stem outwardly and the valve-head 26 against its seat 32. In the bore 35 of the cap 33, a 85 coiled-spring 40 is located, which coöperates with the adjacent end of the sleeve 28 and prevents the latter from being forced too far into the bore 35, thus preventing the valve-head 26 from having excessive movement away from its seat 32. In other words, the power of the compressed air will force the valve-head 26 away from its seat 32, thus exerting pressure on the sleeve 28, which in turn will compress the spring 39, 95 the latter having a normal tendency to hold the valve-head 26 against its seat 32; but, should the air pressure be sufficient to excessively compress the spring 39, the spring 40 in the cap 35 will act as a cushion to receive the impact of the end of the sleeve 28, and will prevent too great movement of the valve-head, cushion the movement of the same and prevent the valve parts from rattling or operating upon each other noisily. 100 105

From the above description, it will be seen that among the advantages of my valve mechanism, the following may be particu-

larly noted: The entire valve structure is removable or detachable from the framework, thus enabling it to be gotten at in all its parts for any special purpose; the valve structure is strong, simple, and cheap; it is effective in operation, always readily responding to the influences of the gas under compression, and its spring mechanism in opposite directions; the valve-head cannot be thrown from its seat in operation, nor assume a position such that its operation or action will become defective; and the valve parts, irrespective of the rapidity of their operation, will be noiseless and cannot chatter.

Having thus described my invention, what I claim and desire to secure by Letters Patent is:

A valve mechanism comprising a frame;

a valve seat secured thereto; a valve coöperating with the seat, said valve carrying a stem; a socketed sleeve for receiving said stem; oppositely disposed journals for supporting said sleeve; a socket in one of said journals; a spring located in said socket and coöperating with one end of the sleeve; a collar on said sleeve; a spring surrounding the sleeve and engaging one end of the collar; and at its opposite end engaging a stationary part.

In testimony whereof I have hereunto signed my name in the presence of two subscribing witnesses.

GEORGE H. REYNOLDS.
